UNITED STATES PATENT OFFICE

LEON L. DUPUIS AND EDWARD HENRY VICARY, OF PORT ANGELES, WASHINGTON

SLITTER DRIVE

Application filed September 20, 1927. Serial No. 220,732.

This invention relates to machines for slitting and trimming paper at high speeds and aims to improve the mounting of the slitters and the driving means therefor. The invention contemplates mounting the slitting cutters on independent arbors or shafts and providing each cutter or slitter with its individual driving motor, thereby enabling adjustments or replacements of the slitters to be made quickly and easily, and eliminating the trouble ordinarily occasioned by vibration of the slitter shafts.

More particularly, the invention relates to improvements in slitting attachments for paper making machines of wide width. Heretofore in slitting the paper web from such machines which, in some instances, approach or exceed twenty feet in width, the shafts carrying the slitter disks are supported in bearings on the side frames of the machine and are subject, when driven at high speed, to considerable vibration and wabbling, resulting in uneven and imperfect slitting of the paper web.

One of the principal aims and advantages of our invention is the improvement of the mounting and driving of the slitter disks so as to avoid the above described condition.

Another aim of this invention is to provide a system of motor control applicable to machines of this type, but not limited thereto, whereby the motors may be started and stopped from a distant point, and whereby either a quick or a coasting stop may be made, the quick stop being accomplished by the utilization of electric current for dynamic braking.

Other objects and advantages of this invention will be apparent from the following specification taken in conjunction with the appended drawings, wherein

Fig. 1 is a longitudinal cross-section, taken on a vertical plane, of a slitting machine embodying the invention;

Fig. 2 is a plan view of a portion of the motor bed assembly;

Fig. 3 is a longitudinal sectional detail view taken on the line 3—3 in Fig. 2;

Fig. 4 is a transverse view of the slitting machine, partly in section and partly in ele-

vation, taken on the line 4—4 in Fig. 1, looking in the direction of the arrows;

Fig. 5 is a diagrammatic illustration of the electrical control and braking means for the slitter driving motors; and

Fig. 6 is a view, partly in section, showing details of a motor bearing and slitter disk mounting.

While our invention is applicable generally to apparatus wherein a moving web of material is to be slit or trimmed, we have herein shown it as applied to a machine of the horizontal type illustrated in Fig. 1, comprising suitable framework 1 whereon rollers, such as 2 and 3, carry a broad web of paper or other sheet material 4, from a source of supply not shown, to a slitter board 5, over which it passes to slitting means located at the point 6, and thence in narrow sheets 7 side by side over a guide roll 8, under the first of a pair of winding rolls 9, onto a core 10. The rolls build up on this core 10 in the manner usual in this art, a full sized roll being indicated at 11. The details of the roll-handling mechanism, including suitable counterweights 12, are of a type known in this art.

The slitter units, which will be described in detail below, are mounted upon a bed transverse to the direction of travel of the paper (see Figs. 1 and 4) comprised of two parallel I-beams 13 placed transversely across the full width of the machine and built into the frame thereof, fastened together at intervals by flanged webs 14, and resting on a concrete foundation 15. The top flanges of these beams, instead of being flat, are formed with inclined top faces meeting in a central crown 16 longitudinally of the beam, and with flat under surfaces 17. (See Fig. 1.) The mounting for each slitter unit is adapted for independent movement along the beams 13. Each mounting comprises a top plate 18 and bottom plate 19, connected by bolts and nuts 20. (See Figs. 2 and 3.) Each top plate 18 is held in alignment on the tops of said beams by a groove in each side complementary to the shape thereof. The bottom plates 19 are adapted to be clamped against the flat under surfaces 17.

of the beam top flanges to secure the mounting in place by setting up the bolts and nuts 20.

Each slitter unit includes an electric motor 21, mounted with its axis parallel to the I-beams 13 upon the top plate 18, upon the shaft 22 of which motor a wheel-like bottom slitter 23 is secured. A knife edge top slitter 24 in the form of a beveled edge disk is 10 loosely journaled in suitable bearings carried by a bracket 25 and adjusted to slightly overlap one side of the bottom slitter. (See Fig. 4.) The motor 21 may be of any usual construction, such as a standard induction motor, either one-phase, two-phase or three-phase.

Referring particularly to Figs. 4 and 6, the bottom slitter 23 is of sufficient diameter to project well above the top of the motor housing, having a widened rim 26, which is smooth, with a flat face and sharp edges. In the particular type of machine constituting the preferred embodiment of our invention illustrated by the accompanying drawings 25 the bottom slitter 23 is about 16 inches in diameter with a rim about 1½ inches wide. This bottom slitter 23 is mounted upon an extension 27 of the motor shaft 22 between two circular hubs 28 and 29 having enlarged 30 flanges 30, 31, with bearing faces perpendicular to the axis of the shaft 27, facing one another and holding the bottom slitter 23 between them. The inner of these hubs 28, is press fitted or shrunk upon the extension 35 27, while the slitter 23 and the outer hub 29 are close sliding fits thereon, and are set up against the inner hub by means of a nut 32 and lock nut 33 on the end of the extension 27.

The bracket 25 comprises a split collar 34 40 or clamp mounted on the cross bar 35 of the main frame, an arm 36, mounted in a lug on the bracket 25, and arranged to be secured in desired vertical adjustment by suitable means such as a clamp screw 37, (Figs. 1 and 45 4) which carries at its lower end an angle bracket or extension 38 in the shape of an inverted L, to the longer, vertical, side of which a horizontal stub shaft 39 is secured.

The top slitter 24 rotates upon this shaft, 50 suitable fastening and lubricating means 40, which it is not necessary to describe in detail being provided. The brackets 25, by means of the clamping collars 34, which are rotatable and slideable upon the shaft 35, may be 55 adjusted and clamped in their respective positions above and parallel to the transverse I-beams 13, to support the upper slitter disks 24 in cooperative relation to the lower slitter disks 23.

10 The arm 36 may be reversed to present the slitter disks 24 to either hand so as to cooperate with either edge of the lower slitters 23, and may be raised to prevent cutting or to permit adjustment or removal of the lower 5 slitters. Thus the slitter disks or cutters of

the several slitter units may be adjusted independently of each other to suit the width of strips to be severed and to make clean cuts, and may be removed independently for sharpening or replacement without affecting the adjustment of the others.

As illustrated by Fig. 6, the bearings of the motor shaft 22, carrying the lower slitter 23, are carried in end bells 41 forming the ends of the motor housing and supporting roller bearings 42 designed to take up end play in the shaft 22. Each end bell 41 includes a rim 43 perforated at intervals for cap screws 44 whereby the bell is fastened to the barrel 45 of the motor housing (see Fig. 6). From this rim a saucer-shaped body 46 extends out, having a re-entrant central hollow boss 47, with arcuate ventilating openings 48. A cover 49 is suitably fastened upon the outside of the boss 47 as by cap screws 50. The motor shaft 22 and extension 27 pass through aligned central bearing holes in the boss and in the cap, these bearings having suitable oil retaining grooves 51, 52. The roller bearing 42 within the boss is of the type having rollers 53 between tapered inner and outer races 54 and 55. The inner race 54 makes a force fit on the shaft, abutting against a shoulder 56 thereon. This race 54 is flanged at both edges to bear against the ends of the rollers 53, and the inclination of the bearing surfaces of both races is such that inward movement of the outer race 55 transmitted through the rollers forces the shaft 22 inwardly. By this means end play in the motor shaft can be taken up by axial movement of the outer race 55. In our preferred construction this axial adjustment is accomplished by an annular bead 57 on the inside of the cover 49, fitting inside the boss 47. This bead 57 bears against the outer race 55 of the roller bearing, and the amount of inward projection of said bead is regulated by insertion or removal of shims 58 between the boss and the cup, and by backing off or setting up the cap screws 50 in the manner usual in such work.

The motors 21 for driving the lower slitters 23 may be of any suitable design adapted for operation by any kind of electric current, but preferably power is supplied by a three wire alternating current circuit 61 and dynamic braking is provided by a two wire direct current circuit 62, both controlled by means of a suitable contactor device including a reversible switch 63 (see Fig. 5), illustrated as of the multi-pole double throw magnetically operated type. The invention comprises a remote control device for the contactor or switch 63 to permit starting and stopping the slitter motors simultaneously, the stopping being accelerated by a dynamic brake of any convenient type. It is contemplated that all the motors in any given installation will ordinarily be of identical size and

design, and will usually carry practically equal loads and operate at substantially the same speed.

While our invention contemplates the use of any standard type of alternating current motor, either three-phase, two-phase or one-phase, in the example illustrated all the motors 21 are of the three-phase type adapted to be connected in a suitable manner to a sixty-cycle three-phase alternating current supply for driving, and to a direct current supply for dynamic braking. The dynamic braking is accomplished by cutting off the alternating current and connecting the direct current across one phase of a polyphase motor or across the field of a single phase motor, as the case may be. The switches in the contactor 63 are interlocked in any manner usual in this art, so that both may be open at once, but to allow only one to be closed at the same time.

Our remote control, for starting and stopping the motors, is operated from a push button station comprising a starting button 64 and a stopping button 65 which actuate the contactors 63 to connect either the power circuit 61 or the braking circuit 62 to the motor leads 66. The push-button circuits are energized by being connected across two of the phase wires of the alternating current supply circuit 61.

The starting button circuit comprises a lead 67 from the middle conductor, through an overload circuit breaker 68, and through contacts which are normally closed by the stopping button 65 when said button is not pressed, but are opened by pressure thereon. The starting button contacts are normally open but are closed by pressure on the starting button 65, allowing flow of current through a solenoid coil 69 in the contactor which throws the switch 63 to connect the supply conductors 61 with the motor leads 66, and back to another phase wire of the supply 61 through a conductor 70. A self-holding contact 71 in a shunt circuit 72 is automatically actuated when the starting circuit is energized, closing the shunt circuit and bridging the gap made when pressure on the starting button 64 is released, so that the solenoid 69 will continue to be energized after release of the starting button. This shunt circuit 72 includes the stopping button 65, and is normally closed thereby, but when the stopping button is depressed the shunt circuit is open and the coil 69 is de-energized.

The stopping button circuit comprises the same lead 67 from the middle conductor and the same overload stop 68 as the starting button circuit just described, together with a contact through the stopping button 65 and the connection 73 leading to another solenoid 74 in the contactor for reversing the switch 63, and through which the conductor 70 the current may return to the other wire

of the three-phase power circuit 61. Overload coils 75 on the outer phase wires of the circuit 61 are provided within the casing of the contactor 63, for operating the circuit breaker 68 to open the starting circuit to stop the motors.

By the operation of the above-described electrical control all motors may be started simultaneously and stopped simultaneously, by pressing the appropriate button 64 or 65. To effect a braking stop the stopping button 65 must be held down until the rotation ceases, for the reason that the stopping control circuit is not provided with means to maintain the circuit through the solenoid 74, when the stopping button 65 is released. A coasting stop of the motors 21 is accomplished by pressing the button 65 only momentarily, thereby de-energizing the self-holding contact 71 and the solenoid 69, and energizing the solenoid 74, to cause the opening of the A. C. circuit. This will also close the D. C. circuit momentarily, but not for a sufficient time to bring about any material dynamic braking, for the reason that the switch 65 will open as soon as the stopping button 65 is released. In this manner the power will be cut off the motors and they will simply die down.

Any suitable type of solenoid operated switch mechanism may be utilized for the contactor that provides for closing the circuit through the motor leads 66, from the alternating current supply 61 when the solenoid 69 is energized, and from the direct current supply 62 when the solenoid 74 is energized, and to open the circuit through the motor leads 66 when neither solenoid is energized.

From the foregoing, it is seen that the electrical features of our invention, diagrammatically illustrated in Fig. 5, comprise suitable connections and control devices for bringing the motors to either a braking stop or a coasting stop, and means for simultaneously controlling all of the motors from a single station.

In the operation of our apparatus the location of the slitter units to make the required cuts in the web is accomplished by sliding each motor to its proper position on the beams 13 and there clamping it, and by bringing each top cutter into corresponding position along the shaft 35 and clamping it in place. The web 4 being threaded through the course shown in Fig. 1, the starting push button 64 is pressed (see Fig. 5) for throwing the switch 63, and putting the alternating current power on the motors 21. The feeding and winding rolls are now started, the web runs through, being cut on the run at the points intended by the slitter units, and the resulting narrow webs 7 are wound up at the far end of the machine into a roll 11, as illustrated in Fig. 1. The supply is replenished and the

finished rolls are removed in any suitable manner usual in this art.

It will be seen from the foregoing that we have invented a slitter drive characterized by accuracy of adjustment and smoothness of operation with resultant straightness and cleanliness of cut, due to the individual mounting of the slitters and to the absence of vibration attendant upon the use of a shaft extending the width of the machine, such as has been used in the prior art to rotate the bottom slitters.

It will be seen from the above description that the slitter units can be adjusted to any position across the machine, either for slitting a web into desired widths or for trimming the edges, and may be removed for sharpening or other purposes, each entirely independently of the others.

Having described a preferred embodiment of our invention, it is to be understood that we do not limit ourselves thereto, but recognizing that the principles of the invention are applicable to other forms of apparatus, we desire to secure by Letters Patent and claim the following:

1. In a web or sheet slitting machine, in combination, a plurality of slitter units, each comprising a bottom slitter secured upon a relatively short shaft, means for independently rotating the shaft of each unit at substantially the same speed, independent supporting means for each of said shafts adjacent to the slitter carried thereby, and a top slitter removably mounted upon a shaft parallel to the axis of the bottom slitter and adapted to coact therewith.

2. In a web or sheet slitting machine, a plurality of slitter units transversely adjustable in an axial direction to cut wide widths of paper or like material into narrow widths, each of said units comprising a bottom slitter secured upon a relatively short shaft, means for rotating the shaft of each unit independently of the other units, and a top slitter adjustably mounted upon a shaft parallel to the axis of the bottom slitters and adapted to coact therewith.

3. In a web or sheet slitting machine, in combination, a plurality of slitter units, each including a bottom slitter rigidly secured upon an independent, relatively short, axially adjustable shaft, and each coacting with an adjustably mounted top slitter, said short shafts being each independently driven at substantially the same speed as the others.

4. In a web or sheet slitting machine, in combination, a plurality of slitter units, each comprising a bottom slitter rigidly secured upon a relatively short shaft mounted independently of the other units, and a top slitter adjustably mounted on a shaft parallel to the axis of said bottom slitter and adapted to coact therewith, said bottom slitter being

axially adjustable and removable independently of said top slitter.

5. In a web or sheet slitting machine, in combination, a plurality of slitter units, each comprising a bottom slitter rigidly secured upon a relatively short shaft mounted independently of the other units, and a top slitter mounted on a shaft parallel to the axis of said bottom slitter and adapted to coact therewith, said top slitter being vertically and laterally adjustable.

6. A slitting attachment for paper making machines of the character described, adapted to slit wide widths of paper into narrower strips, comprising a plurality of slitter units adjustable transversely of the machine, each unit comprising a relatively short shaft, independent driving means for each shaft at substantially the same speed as the other units, a bottom cutter rigidly secured upon each of said shafts, and a top slitter rotatably mounted upon a shaft parallel to the axis of the bottom slitter shaft, said units being independently adjustable laterally with respect to each other, and said slitters being independently removable for sharpening and replacement.

7. In combination, in a slitter, a frame, a plurality of top slitters carried thereby, a transverse beam below said top slitter, a plurality of drive mountings adapted to slide along and to be clamped in position upon said beam, and an individually driven bottom slitter disk upon each of said mountings adapted for coaction with one of said top slitters, thereby to provide for independent positioning and adjustment of said slitters.

8. In combination, in a slitter, a frame, a plurality of top slitters carried thereby, a pair of I-beams transverse thereto, each of said I-beams having a crowned top, a plurality of drive-unit mountings adapted to slide thereon, grooves in said mountings fitting said crowned tops and clamping means cooperating therewith, and a bottom slitter unit mounted on each of said mountings and adapted for coaction with one of said top slitters, thereby to provide for independent positioning and adjustment of said slitters.

9. In a paper slitter of the type described, comprising a series of upper shears and a co-operating series of independently adjustable lower rotating shear units; a mounting for said lower shear units comprising a pair of parallel I-beams in permanently spaced relation, and individual unit mountings co-operating therewith and each comprising a slideable unit-carrying top plate spanning said beams and fitting the top webs thereof, and a bottom plate depending from said top plate and adapted to be clamped against the undersides of said top webs to hold said mounting in adjustment to rigidly maintain its respective lower shear in cooperative position relative to its cooperating upper shear.

10. In a web or sheet slitting machine, in combination, a plurality of slitter units, each comprising a bottom slitter rigidly secured upon a relatively short shaft, said several 5 shafts being independently rotatable and arranged in substantially axial relation to each other, and each unit further comprising a top slitter removably mounted on a shaft parallel to the axis of said bottom slitter and adapted 10 to coact therewith.

11. In a web or sheet slitting machine, in combination, a plurality of slitter units, each comprising a bottom slitter rigidly secured upon a relatively short shaft adapted to be 15 rotated at substantially the same speed as the other units and in axial alignment therewith, said units being independently adjustable laterally with respect to each other, and said slitters being independently adjustable and 20 removable for sharpening and replacement.

12. In a slitting machine for use with paper making machines, a plurality of upper cutters mounted upon a transverse support and axially adjustable thereon, a correspond- 25 ing number of transversely disposed lower slitters for coaction with said upper cutters, a relatively short supporting member for each lower slitter having independent bearings therefor closely adjacent the slitter, and 30 means for driving the lower slitters independently of each other.

13. In a slitting attachment for use with paper making machines, comprising a sup- 35 port extending transversely of the machine, a plurality of lower slitter units slidably mounted thereon and adjustably secured thereto, each of said units comprising a motor bracket, a motor mounted on said bracket and provided with an armature shaft exten- 40 sion, a paper slitting disk detachably secured to said shaft, in combination with cooperat- ing adjustably mounted, disk cutters, each 45 adapted to cooperate with a disk of a lower slitter unit and driven thereby.

14. In a slitting machine, a plurality of upper cutters rotatably suspended from a fixed part of the machine and in spaced trans- 50 verse relation, a plurality of lower slitters each adapted to coact with a corresponding upper cutter to slit paper passing therebetween, a series of short shafts, each carrying one of the lower slitters and arranged in spaced relation transversely of the web of 55 paper, and independent means for rotating each slitter supporting shaft.

15. In combination, in a slitting machine, a cutting unit comprising a top and a bottom slitter, said top slitter including a freely ro- 60 tatable shear supported by a vertically and transversely adjustable arm, and said bottom slitter comprising a driven rotatable shear and driving means therefor mounted upon a common base, said base being transversely ad- 65 justable in parallelism to the adjustment of said arm, whereby either of said rotatable

shears may be brought into operative relation to the other.

16. In a web or sheet slitting machine, a plurality of slitter units transversely adjust- 70 able in an axial direction to cut wide widths of paper or like material into narrower widths, each of said units comprising a bot- 75 tom slitter, individual electric motors for ro- tating said bottom slitters independently of each other and including a relatively short armature shaft on which the bottom slitter is mounted, and a top slitter adjustably mounted upon a support parallel to the axis of the bottom slitter and adapted to coact therewith.

17. In a web or sheet slitting machine as defined in claim 16 characterized by a trans- 80 versely extending beam on which the motors are adjustably mounted, and clamping means for securing said motors in adjusted positions 85 on said beam.

18. In a slitting machine as defined in claim 14 characterized by the upper cutters comprising a cutter-carrying arm adjustably secured in a supporting bracket, said sup- 90 porting bracket being laterally adjustable along the fixed part of the machine.

In testimony whereof, we have signed our names to this specification.

LEON L. DUPUIS.
